UNITED STATES PATENT OFFICE.

CHARLES F. ROPER, OF HOPEDALE, MASSACHUSETTS, ASSIGNOR TO GEORGE DRAPER & SONS, OF SAME PLACE.

AUTOMATIC SPRINKLER.

SPECIFICATION forming part of Letters Patent No. 417,396, dated December 17, 1889.

Application filed June 8, 1889. Serial No. 313,556. (No model.)

To all whom it may concern:

Be it known that I, CHARLES F. ROPER, of Hopedale, county of Worcester, State of Massachusetts, have invented an Improvement in Automatic Sprinklers, of which the following description, in connection with the accompanying drawings, is a specification, like letters on the drawings representing like parts.

This invention relates to automatic sprinklers of that class in which a valve controlling the flow of water is sealed or held closed by means of solder or other suitable material fusible at a substantially low temperature.

My invention has for its object to provide a simple, cheap, and efficient sprinkler; and it consists in an automatic sprinkler having novel features of construction, as will be hereinafter pointed out in the claims at the end of this specification.

Figure 1 shows in vertical section a sufficient portion of an automatic sprinkler embodying my invention as applied to a pipe to enable it to be understood, the valve being shown in its closed position. Fig. 2 is an elevation and section of the sprinkler shown in Fig. 1, the valve being shown open; Figs. 3, 4, and 5, details to be referred to, and Fig. 6 a modification to be referred to.

The pipe A, which may be a main or branch pipe, located, it may be, in a room of a building, is provided at its end, as herein shown, with screw-threads on its inner surface to be engaged by a threaded nipple a, preferably forming part of a casting or valve-casing a', having feet a², to which are secured a plate or disk a³, the said plate, which constitutes the deflector of my improved sprinkler, being fastened to the feet a², which extend through suitable holes in the said plate or disk. The deflector a³ has secured to or forming part of it, as herein shown, a hollow sleeve b, which is extended through the said deflector and projects below the same. The hollow sleeve b is provided on its inner side near its end with preferably inclined shoulders b', (see Figs. 1 and 4,) which support the ends of a valve-stem b² of a valve b³, (herein shown as a disk-valve,) which is extended up into the casting a' when in its normal position. The valve-stem b² is preferably split longitudi-

nally to form two spring-arms 4, (see Fig. 5,) which, when the valve is inserted up into the casting a' into its normal position, are spread or sprung apart and rest upon the shoulders b' of the sleeve b, the said arms being bevelled at their ends, as shown, to more firmly rest upon the said shoulders, to which they may be secured by any suitable solder or like material capable of fusing at a substantially low temperature, the solder also entering between the ends of the arms to aid in keeping them separated.

The sleeve b is herein shown as cut away on diametrically-opposite sides, as at c, (see Fig. 3,) to permit of a free circulation of air into and through it.

The valve b³ will preferably be made of smaller diameter than the diameter of the opening in the casting a', into which the valve is inserted when in its normal position, as shown in Fig. 1, and the said valve is rendered water-tight, as herein shown, by means of plates or disks c', preferably of tin-foil, and a packing c², of paraffine. (Indicated by heavy dark line c", Fig. 1.)

I prefer to employ a valve and disks of tin-foil and a packing c², of paraffine, substantially as shown in Fig. 1; but I do not desire to limit myself to this particular form of valve and means for rendering it water-tight, as other forms may be employed.

In the operation of my improved sprinkler the valve b³, which is normally closed and held in this position by means of the fusible solder securing the arms 4 of the valve-stem 85 upon the shoulder b' of the hollow sleeve, is opened by the pressure of water in the pipe A, when the arms 4 are disconnected from their shoulders by the melting of the fusible solder, which occurs when the temperature 90 in the locality in which the sprinkler is placed has reached a predetermined point. On the melting of the solder the spring-arms 4 come together and resume their normal shape, and the diameter of the valve-stem being less 9 than the diameter of the opening in the end of the hollow sleeve the said valve-stem is forced through the opening in the end of the said hollow sleeve b⁴ by the pressure of the water or other medium in the pipe A, thus 100

forcing the valve b^3 out of the casting a' and down upon the deflector a^3 , as clearly shown in Fig. 2, thereby leaving a free opening or unobstructed passage for the discharge of water in the pipe A upon the deflector a^3 , from which it is thrown in all directions in the form of a spray. The disks c' , as herein shown, rest upon an annular ledge or shoulder c^5 on the interior of the casting a' .

1c I prefer to form the valve-stem integral with the valve and to split it longitudinally to form spring-arms, as described; but I do not desire to limit my invention to this construction, as the valve-stem may be made independently of the valve—as, for instance, as shown in Fig. 6, wherein the valve-stem is made in two separate parts or pieces having their upper end shaped to fit into a socket or recess in the under face of the valve. So, 20 also, it is evident that the valve could be supported by one arm.

I claim—

1. In an automatic sprinkler, the combination, with a valve-casing adapted to be secured to a supply-pipe, of a valve provided with spring-arms forming the valve-stem, a distributer having an opening through which the said arms are extended, and a support secured to said distributer and to which said 30 spring-arms are secured when in operative position, substantially as described.

2. In an automatic sprinkler, the combination, with a deflector and a casting a' , of a hollow sleeve extended below the said deflector and a valve located above the said deflector and provided with a valve-stem extended into the said hollow sleeve, the said valve-stem being split longitudinally to form arms to be secured to the said hollow sleeve 40 when the valve is in its normal or closed position, substantially as described.

3. In an automatic sprinkler, the combination, with a deflector and a casting a' , of a hollow sleeve extended below the said deflector and provided with shoulders b' , and a valve located above the deflector and pro-

vided with a valve-stem extended into the said hollow sleeve, the said valve-stem being split longitudinally to form arms to be secured upon the shoulders of the hollow sleeve, substantially as described.

4. In an automatic sprinkler, the combination, with a deflector and a casting a' , of a hollow sleeve extended below the said deflector and provided with shoulders b' , a valve 55 located above said deflector and consisting of a disk b^3 , plates or disks c' , and a packing c^2 , and a valve-stem secured to the disk b^3 and extended into the hollow sleeve and split longitudinally to form arms to be secured upon 60 the shoulders of the hollow sleeve, substantially as described.

5. In an automatic sprinkler, the combination, with a valve-casing adapted to be secured to a supply-pipe, of a valve inserted in 65 said casing, a spring-arm or valve-stem to support the valve, a distributer secured to said valve-casing and provided with an opening through which the valve-stem is extended loosely, a support attached to said distributer 70 to surround and support the valve-stem when bent from its normal position, and fusible material to retain said valve-stem in abnormal position, substantially as described.

6. In an automatic sprinkler, the combination, with a valve-casing adapted to be secured to a supply-pipe, of a valve, a distributer secured to said valve-casing, and a valve-stem composed of normally-closed spring-arms to support said valve extended through 80 said distributer and independent thereof, a support for said spring-arms, and fusible material interposed between and separating said arms to secure them to their support, substantially as described.

In testimony whereof I have signed my name to this specification in the presence of two subscribing witnesses.

CHARLES F. ROPER.
